[57] **CLAIM**

The ornamental design for a fireplace tool stand, as
shown.

DESCRIPTION

FIG. 1 is a perspective view of a fireplace tool stand
showing my new design;

FIG. 2 is a top plan view thereof;

FIG. 3 is a right side elevational view, the left side being
a mirror image thereof;

FIG. 4 is a front elevational view thereof; and,

FIG. 5 is a rear elevational view thereof.

FIGS. 2-5 have been shown on an enlarged scale with
respect to FIG. 1 and FIGS. 3-5 have been shown
broken away for convenience of illustration.
